(57) **CLAIM**

The ornamental design for a LED utility light with stand, as shown and described.

DESCRIPTION

FIG. 1 is a front perspective view of a LED utility light with stand of the present invention;

FIG. 2 is a left side elevation view thereof;

FIG. 3 is a front elevation view thereof;

FIG. 4 is a right side elevation view thereof;

FIG. 5 is a rear elevation view thereof;

FIG. 6 is a top plan view thereof;

FIG. 7 is a bottom plan view thereof; and,

FIG. 8 is a cross-sectional view taken along the line 8—8 looking upward of the lens detail shown removed for ease of illustration.

The broken line showing of an electrical cord shown in FIGS. 2 thru 7 and two circle details shown in FIGS. 1, 2 and 4 is included for the purpose of illustrating only and forms no part of the claimed design.

1 Claim, 5 Drawing Sheets
